UNITED STATES PATENT OFFICE

2,484,732

ROUNDABOUT

Alton H. Ragsdale, Hemet, Calif.

Application November 18, 1946, Serial No. 710,568

1 Claim. (Cl. 272—33)

1

This invention relates to riding toys.

It is an object of this invention to provide an improved riding toy for children, of the type generally known as a merry-go-round or roundabout, which is formed with a completely covered base and a cycle mounted on the base, whereby the rider may propel the cycle and base.

Another object of this invention is to provide a riding toy of the kind to be more particularly described hereinafter, having a cycle or wheel which the rider may operate with his feet, for operating the toy, the wheel having a cover or guard for completely enclosing the wheel above the platform, whereby the child is protected from falling into the wheel and the platform is made solid so the child, if falling inwardly from the seat, will not fall into the path of the wheels.

Still another object of this invention is to provide an improved riding toy of this kind which is so constructed and arranged that the toy is substantial enough to withstand the hard use to which children put such toys, and provide a maximum amount of protection to the riders in the event that they should fall from the seat.

A further object of this invention is to provide a riding toy which is formed of very few parts, thus providing a very efficient device which is easy to construct and operate, and which provides for the maximum safety of the children riders.

With the above and other objects in view, my invention consists in the arrangement, combination and details of construction disclosed in the drawings and specification, and then more particularly pointed out in the appended claim.

In the drawings,

Figure 1 is a top plan view of a riding toy constructed according to an embodiment of this invention,

Figure 2 is a fragmentary transverse section taken on the line 2—2 of Figure 1,

Figure 3 is a fragmentary section taken on the line 3—3 of Figure 1,

Figure 4 is a vertical section taken on the line 4—4 of Figure 3,

Figure 5 is a transverse section, partly broken away, taken on the line 5—5 of Figure 4,

Figure 6 is a fragmentary vertical section taken on the line 6—6 of Figure 4.

Referring to the drawings, the numeral 10 designates generally a riding toy of the type generally known as a merry-go-round or roundabout, which is adapted to be propelled by a child rider operating the driving wheel. The toy 10 is formed with a base 11 which is adapted to rest or be anchored on the ground, and a pivot post or bear-

2

ing 12 is fixed to the base 11 and extends upwardly therefrom.

A large annular plate or platform 14 engages with the post 12 for rotation thereabout. The platform 14 is formed with a large annular disk or plate which is solid in the plan view thereof, and formed with an opening 15 at the center for engagement about the pivot or post 12.

Radially extending bars 16 are secured to the lower side of the platform 14 by the rivets 17, or other suitable fastening devices, and the bars 16 or supporting members extend outwardly from the opening 15 to the periphery of the plate 14. An annular bearing 18 is fixed to the platform 14 and the supporting members 16 at the center thereof, and extends upwardly above the platform, engaging about the bearing or post 12.

Rollers 19 are rotatably secured to the lower side of the platform 14 by bearings and bearing brackets 20, with the plane of the roller 19 perpendicular to the radius of the platform 14. The rollers 19 are provided to support the platform 14 above the ground and in rolling engagement therewith. The plate 14 is formed with an elongated substantially rectangular opening 21 near the periphery thereof, with the length of the opening 21 perpendicular to the radius of the platform 14. An inverted U-shaped wheel supporting member 22 is fixed to the platform 14 about the opening 21, with the arms of the member 22 rising vertically from the inner and outer edges respectively of the opening 21.

Outwardly extending flanges 24 are formed on the lower free end of the arms of the member 22, and bolts 25 engaging through the flanges 24 and the platform 14 secure the member 22 in position. A wheel 26 is rotatably supported between the arms of the member 22 and a portion of the wheel 26 extends through the opening 21 downwardly below the platform 14 to engage with the ground for rotating the platform upon rotation of the wheel 26.

A guard 27, which is substantially U-shaped in transverse section therethrough, is fixed to the platform 14 on the upper side thereof and encloses the wheel 26 and supporting member 22. The cover or shield 27 is formed with a rearwardly horizontally extending portion 28 for supporting a seat 29 rearwardly of the wheel 26. The cover 27 is formed with a flange 30 which extends outwardly from the lower edge and is secured to the platform 14 by bolts 31 or other suitable fastening means.

The hub or bearing 32 of the wheel 26 is journaled in the supporting member 22 and shield 27

above the platform 14, and a shaft 34 engages through the center of the hub 32 and is connected to the hub by a key 35 on the hub 32. Cranks or pedal supports 36 are fixed to the shaft 34 outwardly of the guard 27 on each side thereof, for supporting the pedals 37 for rotation of the wheel by a rider. The cranks 36 are separated or spaced from the shield 27 by washers 38 between the crank 36 and the side of the shield 27.

Handle-gripping bars 39 are fixed to the cover 27 directly above the wheel by a supporting post 40 fixed to the upper edge of the cover 27 and the bight of the supporting member 22. The seat 29 is fixed to the rearwardly extending portion 28 of the cover 27 by a post 41 fixed to the upper side of the cover 27 rearwardly of the wheel 26 and handle bars 39.

In the use and operation of this riding toy it can be seen that by such construction the wheel is completely covered to prevent the legs or other parts of the child rider from being injured by coming in contact with the wheel and in the event that the child should fall from the seat inwardly of the cycle, he would fall on the solid disk 14 and would not be in a position to be struck or run over by the cycle or any other part of the riding toy.

I do not mean to confine myself to the exact details of construction herein disclosed, but claim all variations falling within the purview of the appended claim.

What I claim is:

A riding toy comprising a rotatable circular

platform having an opening therethrough inwardly from the marginal edge thereof and at right angles to the radii thereof, and an operating unit fixed to said platform on the upper side thereof, said unit comprising a housing fixed to the upper side of said platform over said opening, said housing comprising parallel upright side walls, an upright rear end wall, a front wall and a top wall, a lower flange carried by said opposite side and end walls, means securing said flange to the upper side of said platform, an inverted U-shaped frame fixed in said housing, a crank-shaft journaled through said frame and projecting from opposite sides of said housing, cranks on the outer ends of said shaft, and a traction wheel fixed on said shaft encompassed for the major part thereof by said housing and projecting downwardly through said opening for contact with a plane supporting surface.

ALTON H. RAGSDALE.
